BOWLING ALLEY BUMPER WITH HANGER MEANS

Filed March 13, 1951

UNITED STATES PATENT OFFICE

2,654,605

BOWLING ALLEY BUMPER WITH
HANGER MEANS

Albert B. Hackert, St. Paul, Minn.

Application March 13, 1951, Serial No. 215,265

4 Claims. (Cl. 273—53)

1

This invention relates to bowling alley bumpers or backstops, and more particularly to hanger means for suspendingly supporting same.

Bumpers or backstops for use in bowling to stop balls propelled toward the pins sought to be knocked down comprise a rectangular wooden frame, a rigid backing covering the back face of the frame and forming with the latter an open recess, a flexible cover extending over the front face of the frame and covering the open recess and secured to the frame, and a filler of padding material such as scraps of leather or the like interposed in the open recess and in back of the flexible cover. The top rail of the frame is usually provided with a pair of spaced eye members which project upwardly from the top rail and which are supported in the latter rail. In some instances, the eye members are threaded onto the upper ends of a pair of spaced rods which extend through both the top and bottom rails of the frame and are supported in said rails. The eye members receive the hooks depending from a supporting surface adjacent the bowling alley, and so, the bumpers or stops are dependingly carried solely by the eye members. Due to the fact that the eye members are carried by either the top rail or by the projecting ends of the spaced rods which are supported in both the top and bottom rails of the bumper or backstop frame, the constant striking or pounding of the propelled balls against the flexible cover face of the bumper or backstop causes severe strains and stresses to be exerted upon the frame which strains and stresses in due time result in weakening of the joints of the bumper or stop frame to such an extent as to permit the discharge through the weakened joints of the finely divided powder formed by the battering forces of the propelled bowling balls against the filler contained in the bumper or stop.

An object of the present invention is to provide a hanger means which will serve to suspendingly support a bowling alley bumper or backstop in a manner to resist the weakening of its frame during long periods of use in bowling.

Another object of the present invention is to provide a hanger means which will serve to suspendingly support a bowling alley bumper or backstop and which will enable the bumper or backstop to endure the constant pounding of the propelled bowling balls without weakening of the bumper frame.

A further object of the present invention is to provide a hanger means which is adapted for ready attachment to the bumper or backstop

frame and which is simple in structure and commercially practical.

Other objects and advantages will become apparent from the following description.

An embodiment of the invention is illustrated by way of example in the accompanying drawings wherein

Figure 1 is a front elevational view of a bumper or backstop dependingly supported from a supporting surface adjacent a bowling alley, the bumper frame and the hanger means of the present invention being shown in dotted lines.

Figure 2 is an enlarged perspective view, with a part broken away, of the bumper or backstop of Figure 1, taken from the back, and illustrating the hanger means of the present invention applied thereto.

Figure 3 is an enlarged sectional view taken on the line 3—3 of Figure 1.

Figure 4 is a perspective view of one of the supporting brackets forming a part of the hanger means of the present invention.

Referring to the drawings, the numeral 10 designates a bowling bumper or backstop frame which is rectangular in shape and to the back face of which is secured a rigid backing 11 preferably fabricated of plywood, by means of bolts 17, the backing with the frame forming an open recess 12. Extending over the front face of the frame 10 and covering the recess 12 is a flexible cover 18, the edges of the cover being secured to the adjacent edge portions of the frame 10 and the backing 11. Interposed within the recess 12 and in back of the flexible cover 18 is a filler or padding material 19, such filler or material being scraps of leather or the like.

The hanger means of the present invention comprises a pair of brackets 20 and 21, each of which embracingly engage the adjacent portions of the top rail 23 and the bottom rail 24 of the frame 10, the brackets, as shown in Figures 1 and 3, being spaced from each other and inwardly of the end rails 25 and 26 of the frame 10. Since the specific structure of the brackets is the same, the description of only one of such brackets will suffice for a proper understanding of its structure and its attachment to the top and bottom rails 23 and 24 of the frame 10.

The bracket 20 comprises a flat bar 27 of a length to extend from the lower edge of the bottom rail 24 to the upper edge of the top rail 23 of the frame 10, the bar 27 being provided with spaced apertures 28 and 29 which receive the threaded end portions of bolts 30 and 31 carried by the top and bottom rails 23 and 24 respec-

tively. The threaded end portion of the bolt 30 is in threaded engagement with a thin nut 13 which is received in a complementary recess 14 formed in the back face of the backing 11, while the threaded end portion of the bolt 31 is in threaded engagement with a thin nut 15 which is received in another complementary recess 16 also formed in the back face of the backing 11. The bar 27 is secured in position on the threaded ends of the bolts 30 and 31 by means of nuts 32 and 33 which are also in threaded engagement with the bolts 30 and 31 and bear against the adjacent portions of the bar 27. Projecting from the lower edge of the bar 27 is a leg 34 and projecting from the upper edge of the bar 27 is a second leg 35, the legs 34 and 35 bearing against the top and bottom rails 23 and 24. Arranged longitudinally of the bar 27 adjacent the free end of the leg 35 and secured thereto is an eye member 36 which receives the hook 37 dependably carried by the supporting surface 38. The bracket 21 likewise has an eye member 39 which receives the other hook 40 likewise dependably carried by the supporting surface 38.

If desired, the hanger means of the present invention may also include a reinforcing member or bar 41, the reinforcing member being arranged intermediate and in parallel spaced relation with respect to the pair of brackets 20 and 21 and secured to the top and bottom rails 23 and 24 by means of screws 42 and 43.

By reference to Figure 2, it will be seen that the top rail 23 has two bolts 31 which are equally spaced from each other and from the end rails 25 and 26, and that the bottom rail 24 has two bolts 30 which are likewise equally spaced from each other and from the end rails 25 and 26. In other words, the two bolts 31 are in alignment with the two bolts 30, enabling the reversal of the brackets 20 and 21.

Having thus described the invention, what is new and desired to be secured by Letters Patent is:

1. The combination with a bowling alley bumper comprising a rectangular wooden frame, a rigid backing covering the back face of the frame and forming with the latter an open recess, a flexible cover extending over the front face of the frame and covering the open recess and secured to the frame, and a filler of padding material interposed in the open recess and in back of the flexible cover, of a hanger means for suspendingly supporting said bumper, said means comprising a pair of spaced brackets arranged exteriorly and transversely of said backing and embracingly engaging said frame and fixedly secured to the latter, and an eye member projecting from the end of each of said brackets adjacent the top of said frame for receiving a hook carried by a supporting surface.

2. The combination with a bowling alley bumper comprising a rectangular wooden frame, a rigid backing covering the back face of the frame and forming with the latter an open recess, a flexible cover extending over the front face of the frame and covering the open recess and secured to the frame, and a filler of padding material interposed in the open recess and in back of the flexible cover, of a hanger means for suspendingly supporting said bumper, said means comprising a pair of spaced brackets arranged exteriorly and transversely of said backing and

embracingly engaging said frame and fixedly secured to the latter, an eye member projecting from the end of each of said brackets adjacent the top of said frame for receiving a hook carried by a supporting surface, and a reinforcing bar arranged intermediate and in parallel spaced relation with respect to said brackets and secured to said frame.

3. The combination with a bowling alley bumper comprising a rectangular wooden frame, a rigid backing covering the back face of the frame and forming with the latter an open recess, a flexible cover extending over the front face of the frame and covering the open recess and secured to the frame, and a filler of padding material interposed in the open recess and in back of the flexible cover, of a hanger means for suspendingly supporting said bumper, said means comprising a pair of spaced brackets arranged exteriorly and transversely of said backing and embracingly engaging said frame and fixedly secured to the latter, each of said brackets comprising a flat bar of a length to extend from the lower edge of the bottom of said frame to the upper edge of the top of said frame, a leg projecting from the lower edge of said bar and bearing against the bottom of said frame, a second leg projecting from the upper edge of said bar and bearing against the bottom of said frame, and an eye member arranged longitudinally of said bar adjacent said second leg and integral with the latter for receiving a hook carried by a supporting surface.

4. The combination with a bowling alley bumper comprising a rectangular wooden frame, a rigid backing covering the back face of the frame and forming with the latter an open recess, a flexible cover extending over the front face of the frame and covering the open recess and secured to the frame, and a filler of padding material interposed in the open recess and in back of the flexible cover, of a hanger means for suspendingly supporting said bumper, said means comprising a pair of spaced brackets arranged exteriorly and transversely of said backing and embracingly engaging said frame and fixedly secured to the latter, each of said brackets comprising a flat bar of a length to extend from the lower edge of the bottom of said frame to the upper edge of the top of said frame, a leg projecting from the lower edge of said bar and bearing against the bottom of said frame, a second leg projecting from the upper edge of said bar and bearing against the bottom of said frame, an eye member arranged longitudinally of said bar adjacent said second leg and integral with the latter for receiving a hook carried by a supporting surface, and a reinforcing bar arranged intermediate and in parallel spaced relation with respect to said bars and secured to said frame.

ALBERT E. HACKERT.
